(57) **CLAIM**

The ornamental design for an A-pillar windshield, as shown and described.

DESCRIPTION

FIG. 1 is a front, right side, top perspective view of an A-pillar windshield showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

A mirror image of the A-pillar windshield of FIGS. 1-7 is a second embodiment of the A-pillar windshield.
